UNITED STATES PATENT OFFICE

WILLIAM F. BRINKMAN, JR., OF ST. LOUIS, MISSOURI

SMOKE CONSUMING OR CLEANING DEVICE

Application filed November 28, 1927. Serial No. 236,139.

This invention relates to smoke consuming and cleaning devices.

An object of the invention is to provide equipment for boilers, furnaces and the like, for injecting jets of a mixture of superheated dry steam and preheated air into the boilers and furnaces in a direction to remove the solid and combustible elements from the smoke and to cause more perfect combustion and thereby increase the efficiency of the boilers and furnaces equipped with the device.

Another object of the invention is to provide a novel relationship of the present invention with a boiler or furnace structure, so as to prevent escape of substantial amounts of solid and combustible elements with the smoke and gases passing from the boiler or furnace.

Other objects will appear from the following description, reference being made to the accompanying drawings in which—

Fig. 1 is a vertical longitudinal sectional view of one type of boiler embodying the present invention.

Fig. 2 is a vertical longitudinal sectional view of another type of boiler having the present invention arranged in a different relationship from that shown in Fig. 1.

Fig. 3 is a vertical longitudinal section of one of the steam heating and injecting devices.

Fig. 4 is an outer end elevation of the device shown in Fig. 3.

Figs. 5, 6 and 7 are vertical cross sectional views on the lines 5—5, 6—6 and 7—7, respectively of Fig. 3.

Fig. 8 is a perspective view of a preferred type of nozzle used in connection with this invention.

While I have shown the invention arranged in one relationship in one type of boiler and in a different relationship in another type of boiler, it will be understood that the invention may be applied with equal advantages to other types of boilers and to furnaces.

Fig. 1 will be recognized as a vertical longitudinal section of a familiar type of boiler having a combustion chamber 1 into which fuel may be delivered through a chute 2 or a door 3, as desired. The wall 4 extends above the grate of the combustion chamber 1 and

prevents the passage of solid fuel into the rear chamber 5 which extends below the plane of the grate of the combustion chamber. The smoke and gases from the combustion chamber and bearing solid and other combustible elements rise in the combustion chamber 1 and pass rearwardly above the upper edge of the wall 4 and into and through the chamber 5 to the boiler tubes. By the present invention the solid elements are removed from the smoke and gases and practically all of the combustible elements are consumed in the furnace.

The injector devices are mounted in openings in the walls of the combustion chamber of the boiler and elsewhere, as desired. Each injector device comprises an outer wall 6, an inner wall 7 enclosed within and spaced from the outer wall and united therewith by an outer end wall portion 8 and an inner end wall portion 9 closing the end of the space between said inner and outer walls. A horizontal partition wall 10 within the space between the inner and outer walls of the device at each side of the inner portions 7 extends from the outer end 8 toward the inner end wall 9 and terminates a slight distance from said inner wall 9 leaving an opening through which steam may pass from the under side to the upper side of the partition 10. These partitions 10 are united with the outer and inner walls 6 and 7 and with the outer end wall 8 so that the steam admitted into the outer end of the space below the partition 10 must pass inwardly below said partitions to the inner end wall 9, and thence upwardly above the partitions 10, and outwardly through the space above said partitions to the spray nozzle.

The tube formed by the inner wall 7 is Venturi-like, having a thickened portion 11 flaring outwardly and inwardly and leaving a restricted opening 12 of less diameter than the diameter of the passage through the tube 7 at the inner and outer ends of the device.

The outer wall 11^a of the thickened portion inclines sharply to intersection with the wall 11^b, which forms an opening of approximately uniform diameter to its intersection with said inclined wall 11^a. The inner wall 11^c of the thickened portion 11 in-

clines gradually to the inner end of the tube 11, thus forming a mixing chamber for the superheated steam and preheated air as hereinafter explained.

5 A steam supply pipe 13 opens into each of the devices above described through a branch pipe 14 capable of independent control by valves 15. These branch pipes 14 open into the space below the partitions 10, so that the 10 steam passing from said pipes must circulate as above described. From the outer end of the space above the partitions 10 a pipe 16 has an extension 17 projecting into the outer end of the tube 7 having on its inner end a 15 nozzle 18. The nozzle 18 is in the form of a cap having intersecting slots 19 forming openings through its end wall. The nozzle 18 is located within the outwardly beveled portion 11^a of the thickened area 11 of the tube 7, whereby maximum efficiency in the 20 injection of steam jets through the tube 7 is obtained.

Because of the relationship of the steam inlet pipe 17 and its nozzle 18 to the Venturi tube structure the injection of steam through the Venturi tube draws with it a proper amount of air which becomes thoroughly mixed with the steam in the Venturi tube and preheated to the temperature of the steam 30 before injection into the boiler or furnace. This mixture of superheated steam and preheated air separates the combustible elements from the escaping products of combustion and causes said combustible elements to be 35 thoroughly burned and consumed within the boiler or furnace. The pipe 16 is equipped with a valve 20 to regulate the passage of steam therethrough.

In the relationship shown in Fig. 1 a number 40 of these injector devices are mounted in openings in the combustion chamber wall out of vertical and horizontal alignment and are controllable to inject jets of heated or superheated dry steam transversely and, preferably, longitudinally of the combustion chamber at different heights above the fuel in the combustion chamber. Also, one of these injector devices is preferably mounted in the rear end wall of the chamber 5 below the plane 45 of the upper edge of the wall 4, and another of the injector devices is mounted in one of the side walls of the chamber 5 below the plane of the injector device in the end wall of said chamber. These injector devices are 50 capable of independent control by their valves 15 and 20, previously described. At least one of the injector devices opening through the side wall of the combustion chamber 1 is below the plane of the upper 55 edge of the wall 4, and another of said injector devices is above the plane of the upper edge of said wall 4 and nearer the space above said wall than the injector device that is below the plane of the upper edge of said 60 wall. Thus, the injector devices are ar-

ranged to inject jets of steam to remove combustible elements from the products of combustion passing from the combustion chamber, and to cause said elements to be consumed. Most of the combustible elements 70 that may pass into the chamber 5 are removed from the escaping products of combustion by the injector devices opening through the walls of said chamber 5, as above explained.

75 In the type of boiler shown in Fig. 2, a number of injector devices open through the side wall of the fire box 21 above the level of the fuel therein, and in different horizontal and vertical planes, so as to inject jets of steam to intersect the escaping products of combustion and to remove therefrom the combustible elements. It will be understood 80 that these injector devices are capable of independent control by the valves 15 and 20, so that the injection of steam may be regulated as desired.

85 The inner end walls 9 of the injector devices protrude beyond the inner surfaces of the walls in which the injector devices are mounted, so that the ends of the injector devices become heated to a high degree. Sufficient air may be drawn through the Venturi tubes 7 and mixed with the steam and combustible elements of the products of combustion to obtain nearly perfect combustion of 90 all of said elements.

95 I have found by actual practice of this invention that it is very efficient in connection with different types of boilers and furnaces, and that by proper adaptation the invention may be used in various structures. I contemplate such adaptations and all uses to 100 which the invention may be applied.

I claim:

105 1. In a boiler, walls forming an enclosure, a transverse wall in said enclosure forming a combustion chamber at one side thereof and another chamber at the opposite side thereof constituting a passage for products of combustion, means for producing and injecting thoroughly mixed superheated steam and heated air through one of said walls transversely of said combustion chamber below and above the plane of the upper edge of 110 said transverse wall respectively, and means for producing and injecting said mixture into said combustion chamber toward the space above said transverse wall.

115 2. In a boiler, walls forming an enclosure, a transverse wall in said enclosure forming a combustion chamber at one side thereof and another chamber at the opposite side thereof constituting a passage for products of combustion, means for producing and injecting thoroughly mixed superheated steam and heated air through one of said walls transversely of said combustion chamber below and above the plane of the upper edge of 120 said transverse wall respectively, and means 125

for producing and injecting said mixture into said second chamber toward said transverse wall.

3. In a boiler, walls forming an enclosure, a transverse wall in said enclosure forming a combustion chamber at one side thereof and another chamber at the opposite side thereof constituting a passage for products of combustion, means for producing and 5 injecting thoroughly mixed superheated steam and preheated air through one of said walls into and transversely of said combustion chamber below and above the plane of the upper edge of said transverse wall respectively, and means for producing and 10 injecting said mixture transversely into said second chamber.

4. In a boiler, walls forming an enclosure, a combustion chamber within the enclosure, 20 nozzles forming openings through one of said walls to said combustion chamber, walls forming confined spaces around said nozzles respectively, and means communicating with said spaces and cooperating with said nozzles 25 for producing and injecting into said combustion chamber thorough mixtures of superheated steam and preheated air transversely of the products of combustion passing from the combustion chamber and at different 30 heights.

5. In combination, walls forming an enclosure, a combustion chamber within the enclosure and having a passage therefrom for the products of combustion, nozzles forming 35 openings through said walls to said combustion chamber, means forming confined spaces around said nozzles respectively, and means communicating with said spaces and cooperating with said nozzles for producing 40 and injecting into said chamber transversely of and toward said passage and at different heights thorough mixtures of superheated steam and preheated air.

6. In combination, walls forming an enclosure, a transverse wall in said enclosure forming a combustion chamber at one side thereof, and another chamber at the opposite side thereof constituting a passage for the products of combustion, nozzles forming 45 openings through said first-named walls to said combustion chamber and through one of said first-named walls to said second chamber transversely of the angle of said first-named nozzles and toward said second wall, 50 means forming confined spaces around said nozzles respectively, and means communicating with said spaces and cooperating with said nozzles for producing and injecting therethrough thorough mixtures of superheated steam and preheated air.

7. In a boiler, walls forming an enclosure, a combustion chamber within the enclosure, a Venturi tube extending through a wall of 55 said enclosure and opening into the combustion chamber, means forming a confined

space around said tube, means for admitting steam into said space, means requiring the steam to pass to the end of said tube that is toward the combustion chamber and thence to the outer end of said tube, and means for conducting the steam from the outer end of said space and cooperating with said tube to produce and inject into the combustion chamber a thorough mixture of super-heated steam and pre-heated air.

8. In a boiler, walls forming an enclosure, a combustion chamber within the enclosure, a Venturi tube in one of said walls forming an opening from the outside to the inside of said combustion chamber, means forming a 70 confined space around said tube, means for admitting steam into said space, means in said space requiring the steam to pass to the end of the tube that is toward the combustion chamber and thence to the outer end of said tube, and a tube communicating with said space and extending into said Venturi tube and cooperating therewith to produce and inject into said combustion chamber a 75 thorough mixture of super-heated steam and pre-heated air.

9. In a boiler, walls forming an enclosure, a combustion chamber within the enclosure, a Venturi tube extending through a wall of 80 said enclosure and opening into the combustion chamber, means forming a confined space around said tube, a pipe for admitting steam into said space, a partition in said space requiring the steam to pass to the end of said tube that is within the combustion chamber 85 and thence to the outer end of said tube, a pipe opening from the outer end of said space and extending into said tube for discharging steam from said space into said tube and cooperating with said tube to produce and inject into the combustion chamber a thorough mixture of superheated steam and preheated air, and means for regulating the amount of steam discharged from said pipe.

10. In a boiler, walls forming an enclosure, a combustion chamber within the enclosure, a Venturi tube forming a nozzle opening through one of said walls to said combustion chamber, a wall forming a confined space around said nozzle, means opening into said space for admitting steam into said space, and a pipe opening from said space and extending into said nozzle and cooperating with said nozzle to produce and inject into 100 said combustion chamber a thorough mixture 105 of superheated steam and preheated air.
